UNITED STATES PATENT OFFICE.

JOHN WALDHEIM, OF ELIZABETH, NEW JERSEY, ASSIGNOR TO UNDERWOOD TYPE-WRITER COMPANY, OF NEW YORK, N. Y., A CORPORATION OF DELAWARE.

TYPE-WRITING MACHINE.

1,318,002.

Specification of Letters Patent.

Patented Oct. 7, 1919.

Original application filed October 31, 1916, Serial No. 128,670. Divided and this application filed December 18, 1917. Serial No. 207,762.

To all whom it may concern:

Be it known that I, JOHN WALDHEIM, a citizen of the United States, residing in Elizabeth, in the county of Union and State 5 of New Jersey, have invented certain new and useful Improvements in Type-Writing Machines, of which the following is a specification.

My invention relates to typewriting machines, and more particularly to a tabulating mechanism; and is a division of my co-pending application Serial No. 128,670, filed October 31, 1916.

A feature of the present invention is the 15 provision of a key-set device to be used for selectively setting the machine for column-selecting work.

The stops for column-selecting are, according to the preferred manner of practicing my invention, set individually in any 20 one of a plurality of effective positions, transversely of the stop-bar, so that, with suitable mechanism to coöperate with the variously adjusted column stops, the carriage may be arrested at any selected columnar 25 position or zone.

An additional feature of the invention is that the carriage may be arrested at any selected decimal point in any selected column 30 or zone.

The key-set column-selecting stop device includes a column-selecting stop for each letter-space position of the carriage, and a key-controlled projector for selectively moving the column-selecting stops to effective 35 positions. Preferably, there is provided a plurality of keys in the key-board for moving the projector through different distances.

40 Other features and advantages will hereinafter appear.

In the accompanying drawings,

Figure 1 is a vertical transverse side elevation of the machine, showing the parts in 45 normal positions.

Fig. 2 is a perspective view, showing the key-set device for the column stops.

Fig. 3 is a top plan view of the stop bar, with some of the stops removed.

50 Fig. 4 is a front elevation of the stop bar, showing column stops set in the first, second,

third and fourth columnar positions of the carriage. A fragment of the key-controlled projector is shown, also the denominational stops.

Fig. 5 is a sectional side elevation of the key-set mechanism, showing the "1" key depressed to set a column stop in the column "1" position.

Fig. 6 is a fragmentary sectional side elevation, showing a column stop, set by the projector to the column "4" position.

The typewriting machine is of the regular Underwood construction, of which type-bars 11 swing upwardly and rearwardly to 60 print against a cylindrical platen 12, which rotates on an axle 13, in a carriage 14, which is driven from right to left of the machine by a spring drum 15, connected thereto by a strap 16. The letter-space movements of 65 the carriage are controlled by a suitable escapement mechanism having for this purpose a normally engaged rack 17, which meshes with a pinion 18, connected to the escapement wheel 19, the latter engaging 70 with the reciprocating dogs 20, which are actuated during printing operations by the type-bars 11 and a universal bar (not shown).

To indicate the letter-space position of 80 the carriage, there is provided a pointer 21, on the carriage 14, to coöperate with a scale 22, the latter being fixed on the frame 23 of the typewriting machine.

A decimal tabulator may be provided, as 85 in my co-pending application herein referred to, which may comprise denominational stops 29 at the upper end of plungers 28, which may be moved by suitable keys (not shown) into the path of a column stop 90 30 carried by a stop bar 31; the latter being secured to the typewriter carriage by brackets 32.

The carriage may be released during 95 tabulating operations by the plungers 28 which engage with suitable mechanism, shown in my co-pending application herein mentioned, to lift the rack 17 against the tension of a spring 40 out of engagement with the escapement pinion 18. After the 100 disengagement of the rack 17 from the pinion 18, the carriage is free to run from

right to left of the machine, under the influence of the spring drum 15, until it is arrested by one of the column stops 30, engaging with the actuated denominational 5 stop or coöperative stop 29.

The key-set mechanism comprises a key 43, which, when depressed, swings a lever 44 about a fulcrum 45, against the tension of a spring 46, to cause a downward movement of a stop-setting element or plunger 47. The connection between the lever 44 and the plunger 47 comprises a link 48, connected to an arm 49, located near the left-hand side of the machine and secured to a rock shaft 15/50, and a second arm 51 located near the center of the machine. The upper end of the plunger 47 is provided with a finger 52, the relative position of which, with respect to the denominational stops, is as indicated 20 in Fig. 4.

The column stops, of which there is one on the stop bar for each letter-space position, are normally in their uppermost positions. When it is desired to set any selected column stop to an effective position, the carriage is located by means of the pointer 21 and scale 22, at any desired columnar position or zone, thus locating the selected column stop under the finger 52. 30 The key 43 is then actuated, to move downwardly the stop-setting element or plunger 47, thus moving, by means of the finger 52, the column stop 30 to an effective position.

To restore the stops 30 to their ineffective 35 or neutral position on said bar, which is necessary before setting up a new combination of stops, there is provided on the stop bar 31 a manually-controlled stop-restoring slide 53 (Figs. 1 and 4), which is moved 40 leftwardly on the stop bar, against the tension of a spring 54, to cause an upward movement thereof, by means of shouldered screws 55 and cam slots 56. A stop-engaging portion 57 of the slide 53 underlies 45 fingers 58 of the stops 30; thus, when the slide moves upwardly, the set column stops are moved therewith until arrested by a second finger 58^a formed near the lower edge of the stops 30, and coöperating with 50 the under side of the stop bar 31.

To hold the stops 30 in any position to which they may be set, there is provided for each stop a spring-pressed ball 59, which drops into notches 60 formed on the stop 30.

55 I have provided several keys 43 to coöperate with the lever 44, to move it selectively through different angular distances, thus transmitting a variable movement to the finger 52 of the stop-setting element 47, to 60 set any one of the stops 30, selectively, to any one of a plurality of positions transversely of the stop bar. The keys 43 are provided with key-stems 61, which are guided in suitable slots formed in a U-shaped plate 62, secured to the left-hand

side of the machine frame 23 (Fig. 2), in any suitable manner. The keys 43 have a uniform movement, which is limited by stop pins 63, engaging with the top part of the U-shaped plate 62. The keys move against 70 the tension of springs 64, attached at one end to the plate 62, and at the other end to stop pins 65, on the key-stems 61, engaging with the under side of the plate 62.

The stems 61 engage with bent-off fingers 75 66, on the lever 44, to move the latter through different distances, there being a lost-motion between some of the stems and their coöperating fingers for this purpose. In the drawings, I have shown four keys; 80 thus, any stop 30 can be set to any one of four positions, the position of the latter being dependent upon the key depressed. The four effective positions of the column stops 30 are indicated in Figs. 1, 2 and 4. 85 Referring to Fig. 4, it will be seen that the stops are set, from left to right, in the first, second, third and fourth columnar positions. It will also be seen that the lower ends or engaging portions of these stops are arranged in stepped relation with respect to each other. It will further be seen, that by varying the normal positions of the coöperative or denominational stops 29, and with suitable mechanism used to move the denominational stops through the same distance, when actuated by their respective keys, any one of the denominational stops can be brought selectively into engagement 90 with any one of the set column stops, as disclosed in my co-pending application herein mentioned. The plungers 28 are arranged so that they may be raised or lowered for this purpose by suitable column-selecting mechanism, (not shown), to bring the denominational stops 29 into effective relation with any one of the set column stops. 95

The column-stop-bar 31 (Figs. 3 and 4) comprises two parallel bars 101 and 102, between which are held the column stops 30, 100 in suitable slots. The two parallel bars are separated from each other, and held in relative position, so that the slots in which the column stops move are in perfect alinement, by T-shaped members 103, one at each end 105 of the stop-bar 31. The stop-bar is held assembled by screws 104, which pass through holes in the bar 101 and the members 103, and are threaded into the bar 102.

To give a brief description of the sequence 120 of the operations of my invention, let it be assumed that all of the column stops 30 are in their uppermost or neutral position, on the stop-bar 31, in which position none of the stops are effective.

Starting with the carriage at the extreme right, it is now moved in a letter-space direction until the first columnar position is reached. The column "1" key of the key-set device is now actuated, thus setting a column stop 130

to the second uppermost position, by means of the finger 52, on the stop-setting element 47 (Fig. 5). The key-set mechanism is now restored to its normal position by the spring 46, acting on the key lever 44, and one of the springs 64, acting on the key-stem 61. This same operation is repeated, when the carriage is moved to the second, third and fourth columnar positions, by depressing the column "2," column "3" and column "4" keys, respectively, (for the last position see Fig. 6). Thus the column stops are set, each with its engaging portion in a lower level than the previously set column stops.

15 The column stops have now been arranged on the stop-bar, as indicated in Fig. 4, and the machine is ready for column-selecting. For this purpose, let it be assumed that the denominational stops 29 are in their lowermost effective positions. If one of the tabulator keys is now actuated, the denominational stop 29 will be raised into the path of the column stop 30, in the fourth columnar position. The carriage is at the same time released, to permit the column stop 30 to engage with the denominational stop 29; the latter will at this time be out of range of the column stops, in the first, second and third columnar positions. The denominational position in the column at which the carriage is arrested is dependent upon the tabulator key actuated. If, after again returning the carriage to the right, it is now desired to position the carriage in the first 35 columnar position, the denominational stops are moved to their uppermost effective positions, so that when they are actuated by their keys, they will be brought into the path of the first set column stop on the stop bar. In a like manner the carriage may be positioned in the second and third columnar positions by first setting the denominational stops to their proper effective positions by the column-selecting mechanism.

40 45 It should be understood that, although I have shown only four stop-setting keys, a greater number may be employed.

Variations may be resorted to within the scope of the invention, and portions of the 50 improvements may be used without others.

Having thus described my invention, I claim:

1. In a typewriting machine, the combination with a carriage, of a column selector 55 adapted to skip columns, and comprising column stops, counter stops, and means for selectively setting said column stops to effective positions to vary the column selecting and skipping.

60 65 2. In a typewriting machine, the combination with a carriage, a column selector and a decimal tabulator, of column stops adapted to serve for column selecting and decimal tabulating, and means for selectively setting said column stops to effective positions

to effect column selecting and decimal tabulating.

3. In a typewriting machine, a key-set tabulator comprising column stops, and mechanism for selectively setting said stops 70 to any one of a plurality of effective positions.

4. In a typewriting machine, a key-set tabulator comprising column stops, and mechanism comprising a plurality of keys 75 for selectively setting any one of said stops to any one of a plurality of effective positions.

5. In a typewriting machine, a key-set tabulator comprising column stops, an element 80 for setting said stops, and mechanism for selectively varying the throw of said stop-setting element.

6. In a typewriting machine, a key-set tabulator comprising column stops, an element 85 for setting said column stops to effective positions, and a plurality of keys for selectively varying the movement of said stop-setting element.

7. In a typewriting machine, a key-set 90 tabulator comprising column stops, a stop-setting element, a lever connected to said stop-setting element, and mechanism coöperating with said lever for selectively varying the movement of said stop-setting element. 95

8. In a typewriting machine, a key-set tabulator comprising column stops, a stop-setting element, a lever connected to said stop-setting element, and a plurality of keys 100 engaging with said lever to selectively effect a variable movement of said stop-setting element.

9. In a typewriting machine, comprising a carriage and variably positionable column-selecting mechanism therefor, the combination with said carriage, of a stop bar, a series of variably settable column stops on said bar, and means for selectively setting said stops in variable column-determining positions. 105

10. In a typewriting machine, the combination with a carriage and a column selector comprising a series of column stops, of means for setting said stops to effective 110 positions with their stopping portions out of line. 115

11. In a typewriting machine, comprising a carriage and variably positionable column-selecting mechanism therefor, the combination with said carriage, of a stop bar, a series of variably settable column stops on said bar, means for selectively setting said stops in variable column-determining positions, and means for simultaneously restoring all 120 set stops to normal position. 125

12. In a typewriting machine, the combination with a carriage and a column selector comprising a series of column stops, one for each letter-space position of the carriage, of coöoperative stops, and means for setting 130

- said column stops, individually to any one of a plurality of effective positions.
13. In a typewriting machine, the combination with a carriage and a column selector comprising a series of column stops, one for each letter-space position of the carriage, of means for setting said stops, individually to any one of a plurality of effective positions with their stopping portions out of line.
- 10 14. In a typewriting machine, the combination with a carriage and a column selector comprising a series of column stops, of means for projecting said column stops individually to any one of a plurality of effective positions, and a coöperative stop.
- 15 15. In a typewriting machine, the combination with a carriage and a column selector comprising a series of column stops, of a coöperative stop, and means for projecting said column stops in the direction of said coöperative stop, to any one of a plurality of effective positions.
- 20 16. In a typewriting machine, the combination of a carriage, a series of column stops, means for setting any one of said column stops to any one of a plurality of effective positions on said carriage, said means comprising a projector connected to a lever by suitable linkages, and means for moving said lever through different angular distances.
- 25 17. In a typewriting machine, the combination of a carriage, a series of column stops, means for setting any one of said column stops to any one of a plurality of effective positions on said carriage, said means comprising a projector connected to a lever by suitable linkages, and means for selectively moving said lever through different angular 30 distances, said last-mentioned means comprising a plurality of keys.
- 35 18. In a typewriting machine, comprising a carriage and variably positionable column-selecting mechanism therefor, the combination with said carriage, of a stop-support movable therewith, a stop variably settable in said support in selective column-determining positions transversely of the direction of movement of said carriage, and key-
- controlled means for selectively setting said stop in any one of said column-determining positions.
19. In a typewriting machine, the combination of a carriage, a series of column stops, a coöperative stop, and means for moving any individual column stop transversely to the path of travel of said carriage, to any one of a plurality of effective positions.
20. In a typewriting machine, the combination of a carriage, a series of column stops, a coöperative stop, and means by which said column stops may be moved individually to any one of a plurality of effective positions, said means comprising a plurality of keys.
21. In a typewriting machine, the combination of a carriage, a series of column stops, and means by which said stops may be moved individually to any one of a plurality of effective positions; said means comprising a projector and a plurality of keys, the actuation of said keys being effective to move said projector through different distances.
22. In a typewriting machine, the combination of a carriage, a series of column stops, and means by which said stops may be moved individually to any one of a plurality of effective positions; said means comprising a projector connected by suitable linkages to a key lever, and a plurality of keys coöperating with said key lever.
23. In a typewriting machine, comprising a carriage and variably positionable column-selecting mechanism therefor, the combination with said carriage, of a stop-support movable therewith, a stop variably settable in said support in selective column-determining positions transversely of the direction of movement of said carriage, means for selectively setting said stop in any one of its column-determining positions, means for holding it in any of its set positions when set, and means for restoring said stop to its normal position.
